UNITED STATES PATENT OFFICE.

OTTAVIO GANIO, GIUSEPPE AVONDOLIO, AND ONORATO GRASSIS, OF NEW YORK, N. Y.

ARTIFICIAL-FLOWER-CURLING MACHINE.

Application filed June 16, 1925. Serial No. 37,521.

This invention relates to curling machines and more particularly to artificial flower making apparatus.

In the present practice of artificial flower making, various means have been resorted to and different types of hand tools or instruments have been devised for curling the petals or leaves but for the most part this practice is a slow and tedious one and the work produced is not satisfactory. When manufacturing paper flowers for instance, the material is first cut to produce the petals. Tissue paper or very fine fabric is used, so that a great many may be cut in one operation and it is then the practice of the worker to shape or curl the petals preliminary to assembling the flower. As above stated, the petals must be curled to give a natural appearance and it will be recognized that it results in a slow, tedious and unsatisfactory process where large quantity production is desired.

The purpose and object therefore, of our invention is to produce a machine wherein a large number of layers of cut paper or fabric forms may be curled or rolled in one operation and the individual forms or blanks may be separated, the petals remaining in their curled condition whereupon the flowers may be assembled.

In order to more fully understand and appreciate our invention, reference is had to the accompanying drawings, constituting a part of this application in which,

Figure 1 is a front elevation.

Figure 2 is a sectional view of the clutch mechanism.

Figure 3 is a detailed view, partly in section, showing the clutch shifting lever.

Figure 4 is a detailed view, partly in section, showing the relative position of the clutch shifting lever and the clutch mechanism.

Figure 5 is an end elevation of the machine.

Figure 6 is an enlarged sectional view showing the bottom and top plunger in their relation to the curling mechanism.

Figure 7 is an enlarged plan of the work receiving plate.

Figure 8 is a fragmentary plan of the curler adjusting mechanism.

Figure 9 is a sectional view substantially on the line 9—9 of Figure 8.

Figure 10 is a detailed view showing the petals when curled.

Figure 11 is a plan of the work receiving plate and the support when centered below the top plunger.

Figure 12 is a similar view showing the work receiving plate and its connecting mechanism when crimped.

Figure 13 is an end elevation of the structure as shown by Figure 11.

Figure 14 is an end elevation of the structure shown by Figure 12.

Figure 15 is a partial, sectional view showing the relation of the work receiving plate to the lock or catch shown in Figures 13 and 14.

Referring now to the drawings wherein like reference characters designate corresponding parts throughout the several views, 5, 6, designate the supporting legs of a frame on which the stationary plate 7 is mounted. 75 Depending vertically of the plate 7 is the superstructure 8, which supports the casting or bearing 9 and the curling mechanism, further to be described in detail.

A horizontal shaft 10 is provided with a loosely mounted, continuously rotating gear 11, said gear being formed with clutch teeth 12 and meshing with a worm 13, supported with the driven wheel 14 by an extension bracket 15, attached to the superstructure 8 above referred to. The large wheel 14 is driven by a belt 16 through any suitable source of power. Keyed to the shaft 10, is a bevelled gear 17 and a collar 18. The collar is provided with a clutch tooth 20^a adapted to cooperate with the teeth on the gear 11 so as to drive the shaft 10 and the gear 17. A pin having a bevelled edge 21 is connected by a spring 21^b to the gear 17, said pin being in the path of movement of an adjustable clutch shifting lever 22 whereby the collar is disengaged from the continuously rotating gear 11, permitting the rotation of the shaft and the curling mechanism.

The bevelled gear 17 meshes with a second bevelled gear 22^c located at the top of a vertical shaft 23. A bevelled gear 24 at the lower end of the vertical shaft 23 meshes with a bevelled gear 25 on a horizontal shaft 26, supported between the legs of the frame.

On the shaft 26, there is mounted a lifting cam 27 which is adapted to engage the roller 28 of a plunger 29, said plunger moving upwardly as the roller 28 rides over the surface of the cam 27, above referred to. The plunger 29 operates through a recess in the stationary plate 7 and has attached thereto

the lifting plate 30. A resilient buffer 31 is supported by the stationary plate 7 so as to absorb the shocks to the lifting plate 30 when the plunger 29 drops to the cut away portion of the lifting cam as shown by Figure 5 of the drawings. Attached to the lifting plate are a pair of horizontal guides 32. Centrally of the lifting plate 30, we provide a work receiving, annular, flower forming receiver 33, in the bottom 34 of which is positioned a resilient pad 35 of thick rubber. Within the flower forming receiver 33, is positioned a grooved, bevelled ring 36 between which the petals of the stamped out layers of work 37 are positioned preliminary to the curling and rolling operation subsequently to be described. The receiver 33 is preferably formed with side arms or extensions 38 which slide in the guides 32 when the receiver mechanism is tripped and is moved from its centered position as shown by Figure 11 to the position shown by Figure 12 so that the stamped work may be placed within said receiver preliminary to the curling operation. Connected to the wall of the receiver 33, is a link 38^a and an arm 39 pivotally connected as at 40 and held under tension by a spring 41 connected to a bracket 42^a, attached to the stationary plate 7. A catch or lock 42 is pivoted as at 43 to the adjusting block 65 and adapted to engage the edge of the work receiver 33 when the latter is centered, said locking device being released when the lifting plate 30 drops, which operation is effected after the curling or rolling operation is completed. In other words, the operation of the lifting plunger 29, and the lifting plate 30, which carries the receiver 33 is timed with the curling mechanism so that when the petals are curled, the cam 27 has moved one revolution and consequently the lifting plate 30 is dropped and the receiver 33 is automatically released or moved from the position as shown by Figure 11 to the position shown by Figure 12 whereby the work may be removed and other work inserted in the receiver.

Reference being had particularly to Figures 6 to 9 inclusive of the drawings, showing the details of the curling mechanism, it will be observed that the curlers are operated in unison and are timed so that the curling operation is effected during one revolution of the shaft. The superstructure of frame 8 supports a casting 43 to which the guides 44 are secured. An eccentric 45, mounted on the shaft carries a block 46, slidable in the guide. Connected to the block 46 is a vertical shaft or rod 47, which carries a slotted, annular plate 48. The slotted plate 48 supports the curler operating mechanism which comprises a plurality of radial downwardly extending rods 49 connected at one end to the slotted plate 48 and

at their opposite ends connected to bell crank levers 50. Each bell crank lever is provided with teeth 51 for operating the rack bars 52, which slide in a guide 53, supported by the frame. On the inner end of each rack bar 52, there is provided a curved arm 54 which carries a curling roller 55. The curling rollers and the rack bars 52 are adapted to operate outwardly or away from the center 37 of the form or blanks to be curled, it being of course understood that this operation takes place when the plunger 29 and the lifting plate has been moved upwardly and while the block 46 is being moved upwardly by the action of the eccentric above referred to. The superstructure 8 also carries a block 56, the block carrying a threaded member 59 at whose lower end is held a presser plate 57, a spring 60 being interposed between the block and the presser plate so as to bear firmly on the central portion of the work, positioned in the receiver. In order to regulate the extent of the movement of the bell crank levers and the meshing rack bars, the said bell crank levers have attached thereto a screw 61, which extends through the slotted plate 62 and is retained in a predetermined, adjusted position by the knurled nut 63. Under certain circumstances, it may be desired to increase or decrease the extent of the petal curling operation of the rollers carried by the rack bars 52 and consequently, an adjustment must be provided for the throw of the bell crank lever. In Figure 7, we have also shown a means for centering the work receiver 33 which consists of an adjustable stop 65 which may be moved inwardly or outwardly by the threaded screw 66.

The operation of the machine is under the control of the lever mechanism which consists of the vertical rod 22^a connected to one end of the lever 22, the lower end of the rod 22^a being pivotally connected as at 23^a to the actuating lever 24^a so that when the rod 22^a is moved upwardly and out of engagement with the collar 18, the shaft will rotate very slowly. The plunger 29 will then move upwardly and the shaft 47 downwardly to permit the curlers to engage the work. It will be observed that the clutch shifting lever 22 is provided with a knife edge 22^b which is adapted to ride between the bevelled edge 21 of the pin and the collar 18 thus releasing the clutch, after the shaft 10 has made one complete revolution. At this point, it will be recognized that the curling operation has been effected and that the plunger 29 has dropped, the shaft 47 raised and the work receiver has been moved to the position shown by Figure 12 from which the work may be removed and new work inserted.

Any number of the levers, rack bars and connecting elements may be disconnected or rendered inoperative when different type or

style of forms are to be used, which require curling. In actual practice, the material of the blank is of tissue paper or thin fabric, thus permitting a number to be curled or rolled in one operation. The work is removed from the receiver 33, the curled work is then separated and made into flowers or other designs.

While we have illustrated and described our invention with some degree of particularity, we realize that in practice various alterations therein may be made. We therefore reserve the right and privilege of changing the form of the details of construction or otherwise altering the arrangement of the correlated parts without departing from the spirit of the invention or the scope of the appended claims.

Having thus described our invention, what we claim as new and desire to secure by United States Letters Patent is:—

1. A curling machine of the class described comprising a frame, a work receiver, means for elevating said work receiver, a plurality of curling members operable in unison means for operating said curling members across the work in said work receiver, means for urging the work receiver from beneath the curling members, and a catch for retaining the work receiver in position under the curling members when the receiver is in elevated position.

2. A curling machine of the class described comprising a frame, a work receiver, a plurality of curling members operable in unison when in engagement with the work in said work receiver means for elevating said work receiver into engagement with said curling members, and means for projecting said work receiver from beneath said curling members automatically when a curling operation has been completed.

3. A curling machine of the class described comprising a frame, a shaft supported at the top and bottom of said frame, an eccentric and vertical rod supported thereby operable with the top shaft, a plurality of curlers carried by the said vertical rod, a lifting cam and plunger operable with the bottom shaft, a lifting plate and work receiver carried by the plate on the top of the plunger and gearing for intermittently operating said top and bottom shafts, means for urging the work receiver across said plate, and means on said plate for holding the receiver in position when the plate is raised.

4. A curling machine, of the class described comprising a frame, a gear operated shaft, an eccentric carried by the shaft, a rod attached to the eccentric, a supporting plate, a plurality of links and connected levers carried by the supporting plate, a concentrically movable curler for each set of links and levers, a work receiver a lifting plate for elevating said work receiver into engagement with the said curlers, extensions on said receiver, guides on the plate through which said extensions slide, and means for moving said receiver across said plate at a predetermined time.

5. A curling machine of the class described comprising a frame, a gear operated shaft, a vertical rod and an annular plate carried thereby, means connecting the shaft and rod for lowering and raising the annular plate, a plurality of links and bell crank levers connecting said links attached to the annular plate and frame, concentrically operable curlers movable by the bell crank levers, a work receiver and means for elevating said work receiver in engagement with the curlers, when the annular plate is being lowered, a lifting member across which said work receiver is slidably, said receiver being normally positioned under the curlers during a working operation, and means for urging said receiver from beneath said curlers.

6. A curling machine of the class described comprising a frame, a horizontal shaft supported in the upper and lower portion of said frame, gearing for operating said shafts, automatic means for rendering said shafts inoperative after one complete revolution, an eccentric and a rod attached thereto cooperating with the top shaft, an annular plate carried by the said rod, rack operating mechanism supported by the plate, rack bars and curlers meshing with the said operating mechanism, a lifting plate operable toward and away from the curlers, a work receiver movable horizontally thereacross and adapted to be moved vertically into engagement with the said curlers, and means for automatically causing the horizontal movement of the work receiver across the lifting plate upon a movement of the latter away from the curlers.

7. A curling machine of the class described comprising a frame, a shaft, gearing for operating the shaft, a rod and means for lowering and raising said rod during the rotation of the said shaft, a plurality of curling members and rack bar operating means for spreading said curling members, a lifting plate, a work receiver on said plate movable in engagement with the curlers and means for automatically projecting said work receiver from beneath the curlers.

In testimony whereof we affix our signatures.
